FORREST GRANVILLE PURINTON, OF WATERBURY, CONNECTICUT, ASSIGNOR TO THE PATENT BUTTON COMPANY, OF WATERBURY, CONNECTICUT, A CORPORATION OF CONNECTICUT.

ELECTROPLATING APPARATUS.

1,359,273.

Specification of Letters Patent. Patented Nov. 16, 1920.

Application filed February 25, 1920. Serial No. 361,114.

To all whom it may concern:

Be it known that I, FORREST G. PURINTON, a citizen of the United States, and a resident of Waterbury, in the county of New Haven and State of Connecticut, have made and invented certain new and useful Improvements in Electroplating Apparatus, of which the following is a specification.

My invention relates to electroplating mechanism, and particularly to that class known as plating-barrels.

An object of my invention is to provide an electroplating-barrel apparatus wherein the rotating drum or barrel may be easily and readily raised above and to one side of the plating solution, so as to provide for the easy and ready emptying or recharging of the plating-barrel.

A further object is to accomplish the aforementioned ends in such manner that a single operator is able to move the plating barrel above and to one side of the plating tank, discharge the plated articles from the barrel, refill the barrel and again lower it into the plating solution.

A further object is to provide an electric plating apparatus wherein the tank or tub is provided with an elevating mechanism for moving the barrel or drum up out of the solution and beyond one end of the tank, thus dispensing with the usual hoist and overhead trolley.

A further object is to provide a simple and efficient mechanism whereby the plating barrel is mounted for rotation while immersed in the electroplating solution, may be easily and quickly moved into position for engagement with an elevating track and capable of mounting the track and move above and to one side of the tank when forcibly and manually rotated. A further object is to accomplish the aforementioned ends and at the same time provide means whereby the plating barrel is prevented from moving in a longitudinal direction, so that it will always remain in proper position for mounting the elevating tracks when it is desired to either empty or recharge the same.

With the foregoing and other objects in view which will appear as the description proceeds, my invention resides in the combi-

nation and arrangement of parts and in the details of construction hereinafter described and claimed, it being understood that changes may be made within the scope of what is claimed without departing from the spirit of the invention.

The preferred embodiment of my invention is illustrated in the accompanying drawings, wherein:—

Figure 1 is a view in side elevation of my novel electro plating apparatus, the plating barrel being illustrated in its lowered position and immersed in the electro plating solution.

Fig. 2 is a top plan view of the foregoing.

Fig. 3 is a view in longitudinal section illustrating the plating barrel in its elevated position.

Fig. 4 is a detail view in section taken on the line 4—4 of Fig. 2.

Fig. 5 is a detail view in section taken on the line 5—5 of Fig. 2 illustrating the operation of the lateral shifting mechanism for the rotating drum or barrel.

Fig. 6 is a fragmental view in section taken on the line 6—6 of Fig. 3 illustrating the manner in which the tumbling barrel is held and mounted for free rotation at the upper extremity of its elevated position, and.

Fig. 7 is a detail view of the elevating track wherein the teeth of the track are formed integral with the upstanding sides.

Referring specifically to the several views, wherein similar reference numerals designate corresponding parts throughout, the tank or electrolyte container 10, is provided at its top with the bearing supporting plates 11, and upon which rest the bearing bushings 12, which in turn rotatively support the tumbling barrel shaft or axle 13. The shaft is rigidly secured to, and supports the tumbling barrel 14, overhangs the sides of the tank 10, and is provided at its one extremity with the driving sprocket wheel 15. A chain 16 extends around the sprocket wheel and rotates the tumbling barrel during the plating operation.

The bearing bushings 12, which rotatively support the shaft 13 merely rest upon the supporting plates 11, so as to allow the

tumbling barrel shaft and bearing bushings to be raised and elevated as well as moved to one side or to one end of the tank, as will more fully hereinafter appear.

- 5 In order to prevent the longitudinal shifting of the barrel, the bearing bushings are provided with the ribs 17, which fit within grooves 18, formed in the supporting plates 11. The barrel is held in lateral position 70
 10 upon the bearing supporting plates by the links or arms 19, the ends of which are rotatively secured to the barrel shaft and the opposite extremities are connected to the cross-bar 20. This cross-bar moves within 75
 15 suitable cam slots 21, formed in the plates 22, the latter being rigidly secured to the tub or container 10 as is clearly illustrated in Fig. 1. Thus as the cross-bar 20 is raised or lowered in the cam slots 21, the barrel is
 20 moved laterally along the tank, but due to the ribs and grooves 17, 18, always maintains its proper alignment therein.

Securely fixed to the sides of the tub are the upwardly extending elevating supports 25 or tracks 23, the same being provided with the sprocket engageable chains 24, extending along their periphery. Coöperating with the chains 24 and adapted to elevate or raise the tumbling barrel are the sprocket 30 wheels 25, securely fastened to the shaft 13, and positioned upon the outside of each of the bearing bushings 12. These sprocket wheels are so spaced that they will, upon the lateral movement of the plating barrel engage the chains 24, and upon the forced rotation of the shaft by a suitable hand wheel 26, cause the plating barrel to climb up the rails or supports 23 and in so doing become elevated above and located beyond the top 40 of the tank or receptacle 10.

The plating barrel is provided with the removable segments or doors 27, and in order that these may be brought in convenient and readily accessible position and 45 in order to hold the barrel in its elevated position, I have provided the upper extremities of the supports 23, with what I term disengaging plates 28, the same being comparatively thin in cross section and 50 adapted to contact with and engage grooves 29 formed in the hubs of the sprockets 25. The supporting edges of the disengaging plates are substantially horizontal throughout the majority of their length and then 55 curve sharply upward, so as to form the abutments 30. The rails or supports 24 are curved slightly downward adjacent the disengaging plates, so that as the hubs of the sprocket wheels 25 come into contact with 60 the disengaging plates, the weight of the barrel is gradually removed from the chains and sprocket wheels, and is transferred to the hubs of the sprocket wheels and to the disengaging plates. The further movement 65 and rotation of the barrel results in the dis-

engagement of the sprocket wheels and chains allowing the barrel to freely rotate and without danger of passing beyond the ends of the disengaging plates, due to the presence of the abutments or stops 30.

70 In order to lower the plating barrel from its elevated position shown in Fig. 3, the hand wheel is forcibly turned in the reverse direction, causing the barrel to move along the disengaging plates, until the small sprocket wheels again engage the chains 24.

In order to allow the rail chains 24 to give slightly, I have connected their lower extremities 31 to the resilient arms or springs 32. Thus should the plating-barrel 80 rapidly pass down the elevating rails 23 and continue to rotate upon striking the supporting plates 11, the chains 24 would be prevented from breaking as they would be allowed to move slightly upward by the 85 retraction of the springs 32. After the plating barrel has passed to its lowered position and rests upon the supporting plates 11, the cross-bar 20 is forcibly raised, moving the plating-barrel laterally along the supporting plates and disengaging the small sprocket wheels and chains. Suitable spring latches 33 are secured to the tub and are adapted to engage and hold the cross-bar 90 in its elevated position and accordingly hold the plating-barrel in position for free rotation. The main driving chain 16 which had been removed prior to elevating or raising of the plating-barrel is again passed around the main driving sprocket 15 and thereby 95 provides for the further plating operation. It is to be noted in this connection that I have also found it feasible to elevate the drum by the action of the driving chain 16. Thus when it is desired to elevate and discharge the ingredients of the drum, the latches 33 are moved outwardly and the cross bar 20 moved forcibly downward. This 100 draws the sprocket wheels 25 into engagement with the chains 24 and the forced rotation of the drum by the driving chains 16 causes the barrel to ascend the elevating rails and to move therealong until the sprocket wheels 25 are raised above and out of contact with the chain 24.

110 Secured to the tank 10 and mounted directly below the plating-barrel when the latter is in its elevated position is the funnel or hopper 34, adapted to receive the plated contents of the drum or barrel 14, and guide 115 the same into a receiving receptacle. The elevating supports 23 and the raising chains 24 may, if desired, be formed as a single casting, such as illustrated in Fig. 7. From the foregoing it will be apparent that a 120 single operator is able to raise the plating-barrel from the tank, discharge the plated contents, refill the same, and then return it to the electroplating solution. Further 125 these operations may be performed in a 130

quick and efficient manner, providing for the economical and satisfactory operation of the apparatus. Also attention is called to the fact that the entire elevating apparatus 5 is mounted directly upon the tank, thus making it a self contained unit and doing away with hoists and overhead trolleys.

Having thus fully described my invention, what I claim is:—

10 1. An electroplating apparatus comprising a tank, a plating barrel, inclined elevating rails or supports extending above said plating barrel, and means carried by said plating barrel and adapted to engage said rails and roll along the upper surface thereof to thereby elevate said barrel above said tank.

2. An electroplating apparatus comprising a tank, a plating barrel, elevating rails extending above said tank, means for holding said barrel out of engagement with said rails for the free rotation of the barrel, said means adapted to move said barrel into engagement with said elevating rails, and cooperating means carried by said rails and 25 said barrel adapted to cause the barrel to roll along said elevating rails when rotated.

3. A plating apparatus comprising a tank, a plating barrel, inclined elevating rails carried by said tank, said plating barrel adapted 30 to roll along the upper edges of said elevating rails, means for holding said plating barrel out of engagement with said elevating rails and providing for the free rotation of said plating barrel, said means adapted 35 to draw said plating barrel into engagement with said elevating rails, means carried by said elevating rails and said plating barrel whereby the rotation of said barrel causes the same to roll along said elevating rails 40 and to move above the said tank, and means for rotatably supporting the plating barrel when located at the upper extremity of said elevating rails.

4. An apparatus of the class described 45 comprising a tank, a plating-barrel therefor, means for holding said plating-barrel against longitudinal shifting and allowing the lateral movement thereof, elevating rails carried by said tank, coöperating 50 means carried by said barrel and said rails adapted to cause the positive movement of the barrel by said rails when rotated while being in engagement therewith, and means engaging said barrel adapted to laterally 55 shift the same into engagement with and out of engagement with the said rails.

5. An electro-plating apparatus comprising a tank, a plating-barrel, elevating rails or supports carried by said tank, means engaging said barrel and said tank, allowing 60 the rotation of said barrel, allowing the lateral shifting thereof and holding the barrel against longitudinal shifting, links engaging said barrel and said tank adapted to 65 hold said barrel out of engagement with said

elevating rails, said links also adapted to draw said barrel into engagement with said rails, means carried by said barrel and said rail for causing the positive moving of the barrel along said rail when the former is 70 rotated.

6. An electro-plating apparatus comprising a tank, a plating-barrel, elevating rails or supports carried by said tank, means engaging said barrel and said tank, allowing 75 the rotation of said barrel, allowing the lateral shifting thereof and holding the barrel against longitudinal shifting, links engaging said barrel and said tank adapted to hold said barrel out of engagement with 80 said elevating rails, said links also adapted to draw said barrel into engagement with said rails, means carried by said barrel and said rail for causing the positive moving of the barrel along said rail when the former is 85 rotated, and disengaging plates carried at the upper extremities of said rails, providing for the free rotation of the barrel when mounted thereon and limiting travel of said barrel.

7. An apparatus of the class described comprising a tank, a plating-barrel therefor, provided with a shaft projecting beyond the ends thereof, a main driving wheel mounted upon said shaft, a hand wheel mounted upon 95 said shaft, bearing bushings mounted upon said shaft resting upon the top of said tank, rotatively supporting said barrel and holding the latter against longitudinal shifting and allow the lateral shifting thereof, cam 100 plates mounted upon said tank, links engaging said cam plates and rotatively secured to said shaft, elevating supports mounted upon said tank, toothed wheels mounted upon said shaft and positively engaging the 105 periphery of said elevating supports adapted to cause the barrel to positively move along the said supports when said barrel is rotated, said links adapted to hold said toothed wheels in engagement with or away 110 from said elevating supports.

8. An apparatus of the class described comprising a tank, a plating-barrel therefor, provided with a shaft projecting beyond the ends thereof, a main driving wheel 115 mounted upon said shaft, a hand wheel mounted upon said shaft, bearing bushings mounted upon said shaft resting upon the top of said tank, rotatively supporting said barrel and holding the latter against longitudinal shifting and allow the lateral shifting thereof, cam plates mounted upon said tank, links engaging said cam plates and rotatively secured to said shaft, elevating supports mounted upon said tank, toothed 120 wheels mounted upon said shaft and positively engaging the periphery of said elevating supports adapted to cause the barrel to positively move along the said supports when said barrel is rotated, said links adapt- 125 130

ed to hold said toothed wheels in engagement with or away from said elevating supports, and disengaging plates mounted at the upper extremity of said elevating supports 5 adapted to disengage the toothed wheels and the elevating supports provide for the free rotation of said barrel.

9. An apparatus of the class described comprising a tank, a plating barrel therefor 10 provided with a shaft projecting beyond the end thereof, a main driving wheel mounted upon said shaft, inclined elevating rails mounted upon said tank, toothed wheels mounted upon said shaft and engaging the 15 periphery of said elevating rails and adapt-

ed to cause the barrel to roll along the said rails when said barrel is rotated, links rotatably engaging the shaft of said plating barrel and adapted to hold said toothed wheels out of engagement with said elevating rails 20 and adapted to draw said toothed wheels into engagement with said elevating rails.

Signed at Waterbury, in the county of New Haven and State of Connecticut, this 20th day of February, A. D. 1920.
